Primary Examiner — T. Chase Nelson(74) *Attorney, Agent, or Firm* — Martial Blaise**CLAIM**

(57) I claim the ornamental design for a shoe sole, as shown and described.

DESCRIPTION

FIG. 1 is a top perspective view of a shoe sole, showing my new design;

FIG. 2 is a bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a logo in FIGS. 2 and 8 depict environmental matter and form no part of the claimed design.
